UNITED STATES PATENT OFFICE.

ANDREW P. MORRIS, OF SNYDER, TEXAS, ASSIGNOR OF ONE-TENTH TO C. FRANK SENTELL, OF SNYDER, TEXAS.

DOUBLE-ACTING PUMP.

Continuation of application Serial No. 131,922, filed August 24, 1926. This application filed November 8, 1927. Serial No. 231,859.

My invention relates to pumps and more particularly to double acting pumps for driven wells.

The present application is a continuation 5 of my application for Letters Patent upon pumps, Serial Number 131,922, filed August 24, 1926.

Objects of the present invention are to improve the construction and operation of double acting pumps of the above kind and to 10 provide a construction which is most simple and economical.

One of the main objects of my invention is to provide an improved construction which 15 will enable the plunger rod and all attachments thereto, to be pulled or withdrawn from the pump barrel and the well tubing without pulling or drawing the pump barrel or the tubing from the well.

20 Another object is to provide for a maximum flow of liquid from the pump barrel.

Reference is made to the accompanying drawings which form a part of this application.

25 Figure 1 is a vertical section of a well casing having pumping means therein constructed in accordance with the present invention.

Figure 2 is a section on line 2—2 of Figure 1.

Figure 3 is a horizontal section taken on the line 3—3 of Figure 1, and

Figure 4 is a perspective view of the ring valve for the upper end of the pump barrel.

35 Similar characters of reference are used to indicate the same parts throughout the several views.

Within the well casing 1 is arranged a pump barrel 2 provided at the upper end with a 40 coupling sleeve and composed of two sections 3 and 4 having threaded connection with each other. Discharge pipe or well tubing 5 screws into the upper sleeve section 3, and provided within the latter is an upper check valve 6, 45 which is adapted to engage seat 7 provided in said section 3. The check valve 6 has a central bore through which a hollow plunger or piston rod section 8 travels freely. Sleeve section 4 screws onto the upper end of barrel 2 and is provided with axially extending ports 9 through which the barrel is charged with liquid as the piston 10 of rod section 8 under-

goes its down stroke, on which stroke the liquid in the barrel 2 below the piston is discharged through hollow piston rod section 8 55 into discharge pipe or tubing 5.

In the lower end of hollow piston 10 is a check valve 11 by which the liquid passes into rod section 8 when the down stroke is made. The piston 10 is provided with cup leathers 60 turned up and down, as shown.

The upper end of hollow piston rod section 8 connects to the sucker rod 12 by means of a cage connection 13, allowing liquid passing through hollow piston rod section 8 to pass 65 into discharge pipe or tubing 5 at this point.

On the up stroke of hollow piston 10, barrel 2 is charged with liquid below the piston through a check or standing valve 14 and the liquid already in the barrel, above the piston, 70 is discharged around the upper check valve 6 into discharge pipe 5, said valve 6 traveling upwardly on hollow piston rod section 8 at the same time valve 11 and a ring-shaped check valve 15 are closed. The ring valve 15 75 has a seat 16 of annular concave form on upper end of the annularly and internally thickened lower end portion of the sleeve section 4 through which the ports 9 extend.

The barrel 2 is an open top barrel, and the 80 diameter of all openings above check valve 6, including the internal diameter of discharge pipe 5, are large enough to permit the piston 10 and check valve 6 to be withdrawn with the plunger and sucker rods from the well 85 without pulling or disturbing the barrel 2 or discharge pipe 5. The check valve 14 at the lower end of cylinder barrel 2 may be withdrawn in the same manner, the cage thereof having a removable tapered fit in the fitting 90 17 threaded on the lower end of the barrel.

It will be noted that on the upstroke of the piston, the liquid is driven directly from the barrel into the tubing, thereby resulting in a maximum flow of liquid with a minimum resistance. It will also be seen that the construction is extremely simple and durable so as to be readily manufactured and assembled with economy. Obviously, the lower end of sleeve section 3 limits the opening of ring valve 15 to the proper extent, and due to the weight of the valves 6 and 15, they will seat 95 by gravity in an efficient manner and without the aid of seating springs.

Minor changes may be made without departing from the spirit and scope of the invention as claimed.

What I claim as new is:—

- 5 In a double-acting pump for wells, a cylindrical barrel open at its upper end, well tubing of larger diameter than said barrel, a coupling sleeve embodying a lower section threaded onto the upper end of said barrel,
- 10 said lower coupling sleeve section having a horizontal internal annular valve seat and being formed with axially extending intake ports in its lower end which open at their upper ends through said seat, said seat and
- 15 said port directly surrounding the upper end of said barrel, a downwardly seating ring valve associated with said seat, said coupling sleeve further embodying an upper section

threaded into the lower section and having a horizontal internal annular valve seat, said 20 tubing being connected to said upper coupling sleeve section, a hollow piston rod having a valved piston on its lower end working in said barrel and provided with outlets at 25 its upper end, a downwardly seating check valve slidably fitted on the piston rod and cooperating with the last named valve seat, the last named valve seat having an internal diameter greater than the diameter of the piston, and said check valve having a diameter 30 lesser than the internal diameter of the tubing, to permit free upward removal of the piston and the check valve with the piston rod from the barrel and the tubing.

In testimony whereof I affix my signature.
ANDREW P. MORRIS.
